ABSTRACT OF THE DISCLOSURE

Apparatus for providing a multiple liquid jet consisting of a plurality of substantially concentric jets which are initially contacted with each other without substantial mixing of the liquids in the jets, comprising a plurality of substantially concentric nozzles, passages for supplying different liquids to the nozzles and means for regulating the velocities of the liquids issuing from the nozzles so that adjacent areas of the jets are traveling at the same velocity on initial contact with each other.

Cross reference to related application

This application is a division of copending application Ser. No. 285,764 filed June 5, 1963, now patent No. 3,368,760.

Background of the invention

In the general field of liquid jets, a jet comprised of two or more liquids is desirable for a variety of purposes. First, a jet of one liquid can be utilized for transporting one or more liquids to a desired location by disposing the liquid to be transported entirely within or on the surface of the transporting liquid. Also, the integrity or unity of a liquid jet can be implemented or maintained by coating it with a second liquid having desired characteristics such as high viscosity and/or surface tension characteristics for implementing the integrity of the liquid jet. In the latter instance, the coating liquid can also perform a protecting function with respect to the liquid in the second jet. For example, the coating liquid may protect the liquid jet from contact with the atmosphere to prevent a liquid which would otherwise react physically or chemically with the surrounding atmosphere or enveloping medium from doing so until the jet impinges upon an obstacle where such interaction is desired. In addition, two highly reactive liquids can be conducted to a location in which their reaction is desired by providing a barrier liquid between two liquid jets containing the reactive liquids.

Summary of the invention

The apparatus of this invention provides a multiple component liquid jet, for a desired purpose such as one or more of the above listed purposes, by directing a plurality of jets of different liquids in a parallel relation in which the jets contact each other, and at the initial area of contact the jets are traveling at the same velocity so that there is no mixing of the liquids and there is no momentum transfer between the jets. As a result, a finite area of demarcation is maintained between the liquids in the jets, at least in the vicinity of the area of initial contact of the jets and for a distance thereafter depending on the miscibility of the liquids. As used herein, the term "jet" describes an unsupported free stream of liquid in space which is very long with respect to the diameter of the orifice opening from which it issued. The term "liquid" is inclusive of any liquid-like substance which, when in the form of a jet, is subject to breaking up into a spray or into droplets so that there would be a loss of continuity in the jet body. A plurality of substantially concentric nozzles are

2

connected to passages which supply different liquids to the nozzles. Indicating mechanisms, such as meters, are provided in the passages for indicating a liquid parameter indicative of the velocities of the liquids flowing therethrough, and valves are provided in the passages for regulating the flow therethrough so that the liquids issuing as jets from the nozzles are traveling at the same velocity on initial contact with each other.

Further objects, features and advantages of this invention will become apparent from a consideration of the following description, the appended claims, and the accompanying drawing in which:

FIGURE 1 is a sectional view illustrating one form of the apparatus of this invention for coating a main liquid jet with a layer of a second material which is very thin relative to the thickness of the main jet;

FIGURE 2 is an elevational view, with some parts broken away and other parts shown in section for the purpose of clarity, of a second form of the apparatus of this invention for providing a multiple liquid jet in which the thicknesses of the layers of the different liquids in the jet are more nearly equal;

FIGURE 3 is a sectional view of another form of the apparatus of this invention for providing a multiple liquid jet in which the thicknesses of the layers of the different liquids in the jet are not widely different;

FIGURE 4 is a fragmentary transverse sectional view looking substantially along the line 4—4 in FIG. 3;

FIGURE 5 is a sectional view of another form of the apparatus of this invention for providing a pair of main jets of liquid which are separated by a barrier jet of liquid;

FIGURES 6 and 7 are diagrammatic illustrations of control systems for insuring the desired relative velocities of the jets in the two-liquid forms of the apparatus of this invention illustrated in FIGS. 1 to 4, inclusive; and

FIGURE 8 is a diagrammatic view, illustrated similarly to FIGS. 6 and 7, of a control system usable with the three-liquid form of the apparatus of this invention illustrated in FIG. 5 for providing the same velocities in the liquid jets.

With reference to the drawing, one form of the apparatus of this invention for providing a multiple liquid jet, indicated generally at 10, is shown in FIG. 1 as including a nozzle 12, which may be of any conventional construction, and an auxiliary nozzle 14 which may be either attached to or formed integral with the nozzle 12. The auxiliary nozzle 15 consists of an irregularly shaped body 16 on which a cap 18 is mounted so as to clamp a flexible diaphragm 20 to the body 16. The diaphragm 20 cooperates with a curved side 21 of the body 16 to form an annular cavity 22 which is supplied with material under pressure from a suitable source.

In the use of the apparatus 10, liquid under pressure is supplied to the nozzle 12 so as to form a liquid jet 24 issuing from the nozzle 12 at a given velocity. As used herein, the terms "jet" and "stream" are descriptive of an integral continuous body of liquid moving away from a discharge opening. The body may or may not have a circular cross section although such a shape is the most common. Liquid is supplied to the chamber 22 at a pressure sufficient to move the diaphragm 20, which is stressed so that it normally engages the body 16 so as to close the cavity 22, away from the body 16 sufficiently to form an annular discharge opening 28 and permit the passage of liquid, indicated at 26, out of the chamber 22 adjacent the circumferential surface of the jet 24. The pressure of the liquid supplied to the chamber 22 is such that liquid issuing from the annular discharge passage 28 formed between the diaphragm 20 and the body 16 when the diaphragm 20 flexes outwardly, is traveling at a velocity equal to the velocity of the liquid at the circumferential surface 30 of the jet 24. A multiple component liquid

jet 32 is thus formed consisting of jet 24 and coating liquid 26.

As a result, there is no momentum transfer between the liquids 24 and 26 and no mixing of the liquids 24 and 26 at the point of application of the liquid 26 to the liquid 24, which point approximates the location of discharge opening 28. Consequently, the liquid 26 forms a coating on the liquid 24, which, if desired, may be very thin, i.e. one molecule thick, relative to the thickness of jet 24. This coating can be utilized for a number of advantageous purposes. For example, the jet 24, after it has traveled a predetermined distance, dependent at least in part on the pressure of the liquid supplied to the nozzle 12, breaks up into a spray. However, if the liquid 26 has higher surface tension or viscosity characteristics than the liquid 24 it would maintain the structural integrity of jet 24 beyond the point at which the jet 24 would otherwise breakup into a spray. Also the coating liquid 26 can be utilized to protect the jet 24 against contact with the atmosphere which could be undesirable in the event the jet 24 is formed of a highly volatile liquid or one which would foam or react chemically with the enveloping medium in an undesirable manner. The jet 24 can, when used for fire lighting purposes, be of a character such that it will foam upon contact with air and such foaming at the fire location is desirable. In such case the coating liquid 26 is utilized to prevent premature foaming of the jet 24 prior to the time it reaches the fire.

In some instances, it may also be desirable to supply a powder to the chamber 22 and exert sufficient pressure on the powder in the chamber 22 to force the powder out of the annular discharge opening 28 at a velocity corresponding to the velocity of the circumference of the jet 24. In such case, a powder is chosen which will react or cooperate with the liquid in the jet 24 so as to form a liquid, a solid or a semi-solid film or layer 26 on the surface of the jet 24. As used herein the term "liquid" means any nongaseous liquid-like flowable substance and is inclusive of emulsions, dispersions, resins, colloids, suspensions, composite liquids, and the like in addition to true liquids. The single possible exception to the exclusion of gaseous fluids exists when a gas is used to propel a powder through the discharge passage 28, and in such case the gas leaves the powder and disperses in the medium surrounding jet 24 practically as soon as the powder travels out of the passage 28, so that the gas does not form a part of the jet coating. The term semisolid is used herein to define the range of conditions of materials between liquid and solid. A solid or semi-solid film will implement the integrity of the jet 24 beyond the point at which a liquid coating could function to maintain the integrity of the jet. Also, the jet 24 may be used in this manner for rapidly forming a solid or semi-solid tubular member from the coating 24.

In some instances, the jet 24 can also be utilized to transport small amounts of the material 26 to the desired point of use. For example, the material 26 can be a fire inhibitor and can be transported on the jet 24 of water to the fire location. In some instances it is also desirable to form the member 20 of a metallic-like material in which case the opening 28 is of a fixed size during a given use of the apparatus 10.

In FIG. 2, a second form of a "two-liquid" multiple component liquid jet apparatus is illustrated and indicated generally at 40. The apparatus 40 includes a first nozzle member 42 which has a pair of branch conduits 44 attached to or formed integral with the nozzle 42. A second nozzle 46, arranged substantially concentrically within the nozzle 42 and supported thereon on struts 48, which may be very thin or of streamline shape, is connected to a conduit 50 which is telescoped within one of the branch conduits 44. This purpose of the apparatus 40 is to provide a composite jet 52 which consists of an inner core jet 54 and an outer annular jet 56 which contacts and encircles the core jet 54.

In the use of the apparatus 40, liquid 58 is supplied to the inner nozzle 46 so that it issues therefrom in the form of the core jet 54. A second liquid 60 is supplied to the outer nozzle 42 and the struts 48 act to smooth out the flow of this liquid as it travels toward nozzle 42. The liquid issues from nozzle 42 in the form of the annular jet 56, and the velocities of the jets 54 and 56, at their point 62 of application one to the other are the same. As a result, there is no mixing of the liquids in the jets 54 and 56 at the point 62 and substantial mixing of the liquids is avoided until a point downstream from the point 60 is reached at which the jets lose their momentum.

The apparatus 40 can be advantageously utilized for transporting the jet 54 to a desired point of use when contact of the jet 54 with the atmosphere prior to reaching the point of use of the jet 54 would have an undesirable effect on the jet 54. For example, the jet 54 may have a foam content such that air currents would destroy its integrity, which is avoided when the jet 54 is protected by the jet 56 which may be of a liquid such that contact with the atmosphere is not undesirable. Furthermore, the jet 56 will function to prevent contact of the jet 54 with the atmosphere when mere contact of the jet 54 with air would have an undesirable change in the characteristics of the jet 54. For example, the jet 54 may be a liquid which will foam or evaporate or react chemically or physically on contact with air. In such case, the apparatus 40 is useful in projecting the jet 54 during travel over a distance through which it could not otherwise be moved. Also the jet 56, when formed of a liquid having low thermal conductivity characteristics will act as insulation for the jet 54.

In FIG. 3 still another form of the "two-liquid" multiple component liquid jet apparatus of this invention is illustrated and indicated generally at 70. The apparatus 70 includes an outer nozzle 72 which is attached to or formed integral with a body 74 having a tubular portion 76 which communicates with a suitable source of liquid under pressure. The body 74 is in the form of a streamline strut which acts to straighten the liquid flowing from the tubular member 76 to the nozzle 72 and is formed with a through opening 78 in which a rotatable valve body 80, having guide vanes 81 in the passages therein, is positioned. The opening 78 on one side of the body 80 is connected through a conduit 82 or the like, with a source of a second liquid 84 which is likewise under a suitable pressure. The opening 78 on the opposite side of valve body 80 is connected through a conduit 83 or the like with a liquid different from the liquid 84 and which may be the same liquid supplied to the tubular member 76. In the position of the valve body illustrated in FIG. 3, the liquid 84 is free to flow through the valve body 80 and thence through an inner nozzle 86 which is likewise formed as an attachment for or integral with the body 74. In a second position of the valve body 80, moved about ninety degrees relative to the position shown in FIG. 3, communication of the liquid 84 with the nozzle 86 is blocked at the valve 80, and the nozzle 86 is communicated with liquid from the conduit 83.

In the use of the apparatus 70, a multiple component liquid jet 88 is formed which includes a core jet 90 of one liquid and an outer annular jet 92 of a different liquid which surrounds the core jet 90. The multiple liquid jet 88 is obtained by first supplying the desired liquid to the tubular member 76, when the valve 80 is in its closed position preventing flow of liquid 84 to the nozzle 86, to form jet 92. The same or a different liquid is at this time also supplied to the conduit 83 to fill the core of jet 92. The valve 80 is then rotated to its position illustrated in FIG. 3 so as to form the core jet 90 within the annular jet 92, with the outer end of jet 90 covered by the liquid supplied to conduit 83 so as to prevent contact of the outer end of jet 92 with the surrounding atmosphere or medium. The pressures on the liquids which form the jets 90 and 92 are adjusted, as explained hereinafter in detail, so that

at the point of application 94 of the jets to each other, the jets are traveling at the same velocity. The apparatus 70 is thus particularly adapted for situations in which the outer end of jet 92 must be prevented from contact with the surrounding medium because the liquid in jet 92 is highly reactive.

In FIG. 5, a form of the apparatus of this invention for obtaining a "three-liquid" multiple liquid jet is illustrated and indicated generally at 100. The apparatus 100 is capable of providing a three-liquid jet 102 which consists of an inner or core jet 104, an outer enclosing jet 106, and a barrier jet 108 disposed between and preventing contact of the jets 104 and 106. The apparatus 100 consists of a hollow conduit 109 which is supplied with a desired liquid for forming the jet 106 and which terminates at one end in a nozzle 110. A streamline strut 112 in the conduit 109 is formed on one side with a nozzle 114 which is in liquid communication with a tubular conduit 116 disposed on the opposite side of the strut 112. Liquid under pressure is supplied through the tubular member 116 to the nozzle 114 so as to form the core jet 104. An annular cavity 118 formed within the nozzle 114 communicates through a passage 120 in the strut 112 with a source of a third liquid under pressure which forms the barrier jet 108. A third nozzle 122 having an annular discharge opening 124 is formed within the nozzle 114.

In the use of the apparatus 100, a first liquid is supplied to the nozzle 110 so as to form the enclosing jet 106, a second liquid is supplied to the nozzle 114 so as to form the core jet 104 and a third liquid is supplied through the passage 120 to the cavity 118 so that it issues from the nozzle opening 124 to form the barrier jet 108 which separates the jets 104 and 106. At the point of application of the barrier jet 108 to the core jet 104, which point corresponds to the opening 124, the jets 104 and 108 are traveling at the same velocity. Likewise, at the point of application of the jet 106 to the barrier jet 108, the jets 106 and 108 are traveling at the same speed.

The apparatus 100 is usable for a variety of purposes. For example, in the event the liquids which comprise the jets 104 and 106 are reactive and their reaction is desired at a point remote from the apparatus 100, the barrier jet 108 functions to maintain the liquids in the jets 104 and 106 out of contact with each other until they reach the desired point of reaction. The liquid which comprises the jet 108 in such case is nonreactive with both the liquids which comprise the jets 104 and 106 and might also function to maintain the structural integrity of the jet 104. It is to be understood that while a maximum of three liquids in a single jet have been illustrated in FIGS. 1 to 5, inclusive, this number may be increased merely by providing additional nozzles, when the purposes of the jets are best accomplished by adding still more liquids.

Several systems are illustrated in FIGS. 6 to 8, inclusive, for regulating the velocities of the different liquids in the multiple component liquid jets illustrated in FIGS. 1, 2, 3, and 5 so that at the initial point of contact of liquids which contact each other, they are traveling at the same velocity. The contact of the liquids at the same velocity prevents mixing of the liquids, prevents any transfer of momentum between the liquids, and provides for at least an initial finite line of demarcation between the liquids. The system illustrated in FIG. 6, and indicated generally at 130, is illustrated applied to the apparatus 10, but it is to be understood that it is equally applicable to any other "two-liquid" multiple component liquid jet device such as the ones shown in FIGS. 2 and 3. The system 10 includes a conduit A which supplies the liquid 26 to the cavity 22 and a conduit B which supplies the liquid which forms the jet 24. A meter unit 132 which may be in the form of a pressure gauge or a flowmeter, such as a meter of venturi type, is installed in the conduit A in series with a manual valve 134. A similar meter 136 is installed in the conduit B in series with a manual valve 138. Once the area of the outlet opening in the nozzle 12 is ascertained, and

the area of the outlet opening 28 necessary to provide the desired thickness of the liquid layer 26 on the jet 24 is ascertained, the readings on the meters 132 and 136 necessary to obtain equal velocities of the jet 24 and the liquid 26 at the point of application of the liquid 26 to the jet 24 is readily computed. The valves 134 and 138 are then manually adjusted to obtain these readings on the meters 132 and 136. The system 130 is readily adapted to a "three or more" liquid multiple jet apparatus by merely increasing the number of valves and meters. The meters 132 and 136 may also be incorporated in a single gauge or meter unit connected to conduits A and B so as to indicate relative pressures in conduits A and B.

The system illustrated in FIG. 7, indicated generally by the numeral 140, accomplishes the same result that is accomplished with the system 130 but accomplishes it automatically. The system 140 is also illustrated as applied to the apparatus 10 but it is to be understood that it is equally adaptable to the devices shown in FIGS. 2 and 3. The system 140 includes conduits A and B which supply liquid to the apparatus 10 and includes meters 142 and 144 like the meter 132 described above. A manual valve 146 is interposed in the conduit B and an automatic regulating valve 148 is interposed in the line A and connected to a pressure comparator 150, of well known construction, which is also connected to the meters 142 and 144. The comparator 150 is suitably connected to meters 142 and 144 and functions to compare the parameters (related to liquid velocities) measured by the meters 142 and 144 and to actuate the regulating valve 148 in accordance with the comparison of these parameters so as to maintain a predetermined desired relationship between the velocities of the liquids in the lines A and B. This desired relationship is computed to provide for equal velocities of the liquid 26 and the jet 24. The valve 146 is adjusted to provide the desired flow rate. The meters 142 and 144, the regulator valve 148 and the comparator 150 may also be incorporated in a single unit suitably connected to conduits A and B.

In FIG. 8 a system 160 is illustrated which is applicable to the "three-liquid" apparatus 100 so as to automatically regulate the velocities of the jets 104, 106 and 108 to maintain equal velocities of the jets. The system 160 includes a conduit A which supplies the liquid which forms the jet 104, a conduit B which supplies the liquid that forms the jet 106, and a conduit C which supplies the liquid that forms the jet 108. A meter 162 is interposed in the conduit A in series relation with a manual valve 164. A pressure comparator 166, connected to the meter 162 for actuation thereby, is connected to a pressure regulating valve 170 in the conduit C. The comparator 166 is preset so that it adjusts the valves 168 and 170, in response to actuation by the meter 162, so as to maintain the jets 104, 106 and 108 of equal velocities. The manual valve 164 is adjusted to maintain the desired flow through the conduit A. The desired setting of the comparator 166 is computed once the areas of the discharge outlets of the jets 104, 106 and 108 is known so as to maintain the desired velocities of the jets. Additional meters 172 and 174 are illustrated in broken lines in FIG. 8 in the conduits B and C for the purpose of illustrating that separate meters for the pressure comparator 166 may, if desired, be installed in the lines A, B, and C, or structure for accomplishing the functions of the meters 172 and 174 can be incorporated in the comparator 166 and/or the valves 168 and 170.

It will be understood that the apparatus for providing multiple liquid jets which are herein disclosed and described are presented for purposes of explanation and illustration and are not intended to indicate limits of the invention, the scope of which is defined by the following claims.

What is claimed is:

1. Apparatus for providing a multiple liquid jet comprising a plurality of substantially concentric nozzles

arranged so that liquid jets issuing under pressure from concentrically adjacent ones of said nozzles will be in contact with each other without substantial mixing of the liquids in the jets, said apparatus comprising passage means for supplying different liquids to said nozzles, indicating means in said passage means capable of indicating a liquid parameter related to the velocities of the liquids therein, and adjustable valve means in said passage means for regulating the flow therethrough so that the liquids issuing as jets from said nozzles are traveling at the same velocity on initial contact with each other.

2. Apparatus according to claim 1 wherein said indicating means consists of meters.

3. Apparatus according to claim 1 further including a multiple position valve communicating with the inner one of said nozzles, said valve being movable between a position closing said inner nozzle and a position directing liquid from one of said passage means to said inner nozzle.

4. Apparatus according to claim 1 wherein the outer one of said nozzles is formed by a flexible diaphragm, and wherein the concentrically adjacent nozzle to said outer nozzle is a tubular member, and means mounting said diaphragm for movement into a closely spaced relation with said tubular member for flow of an annular jet of liquid therebetween.

5. Apparatus according to claim 1 wherein said substantially concentric nozzles are formed by three tubular members arranged substantially concentrically so that the intermediate one of said members is in a closely spaced relation with the inner one of said members and spaced further from the outer one of said members so as to provide a multiple liquid jet having three components in which the intermediate component is thin relative to the inner and outer components.

6. Apparatus according to claim 1 further including flow comparator means, and wherein said indicating means includes flow responsive means in one of said passage means connected to said comparator means so as to actuate said comparator means, and a regulating valve to another one of said passage means responsive to actuation of said comparator.
